UNITED STATES PATENT OFFICE.

SOLOMON RITTER HIPPLE, OF WILLIAMSPORT, PENNSYLVANIA, ASSIGNOR TO DX INSTRUMENT COMPANY, OF HARRISBURG, PENNSYLVANIA, A CORPORATION OF DELAWARE.

RHEOSTAT.

Application filed December 5, 1922. Serial No. 605,048.

To all whom it may concern:

Be it known that I, SOLOMON RITTER HIPPLE, a citizen of the United States, residing at Williamsport, in the county of Lycoming and State of Pennsylvania, have invented certain new and useful Improvements in Rheostats; and I do hereby declare the following to be a full, clear, and exact description of the invention, such as will enable others skilled in the art to which it appertains to make and use the same.

This invention relates to improvements in rheostats of that type in which a compressible conductive medium is interposed in the circuit to be controlled, means being provided for varying the compression of the medium to vary the resistance thereof. It has for its object the provision of a device in which a very delicate regulation of the compression of the resistance medium can be obtained that particularly adapts the device to radio installations.

In carrying out the invention, a compressible resistance medium is placed in an insulating container, between two coiled springs of different strengths, mounted in the opposite ends of the container, the springs and the interposed resistance medium being adapted to be compressed to any desired extent by means of a regulable adjusting means, preferably in the form of a screw, threaded into one end of the container and cooperating with the proximate spring. Owing to the differential strengths of the respective springs, a large element of the compressive force applied by the adjusting screw will be taken up by the weaker of the two springs, and the remainder of the force will be effected in compressing the resistance medium. If the compressive action of the screw be continued, the resistance medium is still further compressed until it offers sufficient opposition to cause the stronger spring to take up its proper proportion of the force, so that, when the maximum stage of compression is reached, both springs are practically collapsed. During the compressive action applied by the adjusting screw and the cooperating differential springs, the compressive force exerted on the resistance medium may be varied to the minutest degree, thereby varying the resistance to the flow of current proportionately, which admirably adapts the device to radio systems

and similar installations wherein a particularly fine adjustment of resistance is essential.

In the drawings, Fig. 1 shows a sectional view of one structural embodiment of the invention, and

Fig. 2 shows a similar view of another structural embodiment.

Referring to the drawings, more particularly to Fig. 1 thereof, 5 designates a cylindrical container of lava, or other suitable non-conductive material, closed at one end and open at the other. Threaded in the open end of the container is the metal plug 6 having a reduced extension 7. In mounting the rheostat the extension 7 is placed in an opening 8 of the panel 9 and a nut 10 turned onto this extension against the outer face of the panel clamps the rheostat in place. The extension also forms a binding post and by a second nut 11 thereon an end of the wire conductor (not shown) can be attached thereto. Seated in the closed end of the container is a screw 12 which, with the nuts 13, forms the other binding post for the wire conductor.

Threaded through the extension 7 and the body part of the plug 6 is the adjusting screw 14 with a thread of very small pitch. On the outer end of the screw is the hard rubber or fibre hand-wheel 15 for turning the same. In one end of the container, adjacent to the inner end of the adjusting screw 14, is the comparatively strong spring 16, and in the other end of the container is the comparatively weak spring 17. On opposite ends of the spring 16 are the metal caps 18 and 18' respectively, and on opposite ends of the spring 17 are the metal caps 19 and 19' respectively. The inner end of the screw 14 normally impinges on the cap 18 and the cap 19' is secured to the end wall of the container by the screw 12. Contacting with the inner faces of the caps 18' and 19 are the opposite fibre disks or washers 20 and 21 respectively and between these disks is the resistance medium 22 of granular conducting material, such as comminuted carbon or a mixture of such carbon and suitable granular metal. The disks 20 and 21 fit the bore of the container closely so as to confine the granular material between them and both disks have a central opening so that the granular material can make an ef-

fective electric contact through the disks with the metal caps 18' and 19 adjacent to said disks. The metal caps 18, 18' and 19 fit the bore of the container rather loosely so that they can easily move therein. The springs 16 and 17 are normally under tension and exert opposing forces against the opposite ends of the resistance medium 22 and the compression so exerted normally tends to pack the material more or less and its conductivity or resistance is effected thereby. By turning the adjusting screw 14 the compression of the resistance medium can be regulated.

15 In the operation of the device, the terminals of the conductor, of which it is desired to regulate the resistance, are attached to the binding posts provided by the extension 7 and the nuts 10-11 and by the screw 12 and nuts 13. In this way the circuit is established between the terminals of the conductor, through the extension 7, the plug 6, the screw 14, the cap 18, the comparatively strong spring 16, the cap 18', the resistance medium 22, the cap 19, the comparatively weak spring 17, the cap 19' and the screw 12. Should it be desired to vary the resistance of the conductor, to lessen it for an instance, the screw 14 is turned into the container, thereby applying a compressive force to the springs 16 and 17 and the interposed resistance medium. During the initial part of the compression there will be hardly any deformation of the stronger spring, but the weaker spring will be deformed to some extent and the remainder of the energy will be applied in compressing the resistance medium. A slight inward adjustment of the regulating screw will result in a very slight compressive action on the resistance medium; consequently, a very delicate adjustment of the compression in the resistance medium may be effected, which is very desirable in radio work.

45 The structural embodiment of the invention shown in Fig. 2 is quite similar to that shown in Fig. 1. In the second structural form the resistance medium 22' is formed by a pile of disks of carbon or other suitable material. By regulating the compression of this pile, as in the granular formation, the resistance of the medium can be varied. In the second form the fibre disks 21 of the first form are eliminated as the carbon disks of the pile need no confinement and can bear directly on the metal caps 18' and 19. Also, in the second form the metal plug 6' has a binding post formed by an inwardly turned lip 7' and holding screw 11'. In other respects the second structural form is the same as the first and operated in the same way.

What I claim is:

1. A rheostat comprising an insulating casing, differential springs in the opposite ends of said casing, a compressible resist-

ance medium interposed between said springs, and adjusting means at one end of the casing for applying accurately regulated pressure to the springs and the interposed resistance medium.

2. A rheostat comprising an insulating casing, differential springs in the opposite ends of said casing, a compressible resistance medium interposed between said springs, and an adjusting screw mounted in one end of said casing cooperating with the adjacent spring for applying accurately regulated pressure to the resistance medium through the differential action of the springs.

3. A rheostat comprising an insulating casing, a body of compressible resistance material therein, differential springs in opposite ends of the casing between which said material is confined, an adjusting screw mounted in one end of said casing cooperating with the adjacent spring for applying accurately regulated pressure to the resistance medium through the differential action of the springs, and line terminals connected with said screw and the spring in the remote end of the casing.

4. A rheostat comprising an insulating casing, a binding post in one end of the casing, a plug in the opposite end thereof, differential springs in the opposite ends of the casing, conducting disks engaging the inner ends of the springs, a compressible resistance medium confined between said disks, and an adjusting screw threaded through said plug cooperating with the adjacent spring for applying accurately regulated pressure to the resistance medium through the differential action of the springs.

5. A rheostat comprising an insulating casing, differential springs in the opposite ends of the container, metal caps on the inner ends of the springs, a compressible resistance medium in the container between said caps, and regulative means for applying pressure to the springs and the interposed resistance medium.

6. A rheostat comprising an insulating casing, differential springs in the opposite ends of the container, a granular resistance medium in the container between said springs, washers in the container between the ends of the springs and the adjacent resistance medium to hold the granular material in place, and regulative means for applying pressure to the springs and the interposed resistance medium.

7. In a rheostat of the compression type, the combination of a cylindrical container formed of insulating material, springs in the opposite ends of the container, metal caps on the inner ends of the springs, a granular resistance medium in the container between said caps, washers in the container between the caps and the adjacent resistance

medium to hold the granular material in place, said washers having openings to permit electrical contact between the adjacent caps and the granular material of the resistance medium, and regulative means for applying pressure to the springs and the interposed resistance medium.

8. In a rheostat of the compression type, the combination of a cylindrical container formed of insulating material closed at one end and open at the other, a metal plug seated in the open end of the container and having a threaded extension provided with clamping nuts to attach thereto a wire terminal and to attach the rheostat to a sup-

port, springs in the opposite ends of said container, metal caps on the opposite ends of each spring, a screw passing through the wall at the closed end of the container and adjacent cup and having clamping nuts on its end projecting outside of the container to connect a wire terminal thereto, a resistance medium in the container between the springs, and a regulating screw threaded through said plug and operative to compress the springs and the interposed resistance medium.

In testimony whereof I affix my signature.

SOLOMON RITTER HIPPLE.
